UNITED STATES PATENT OFFICE

2,490,475

GARMENT HANGER

Solomon Rosenberg, Los Angeles, Calif.

Application October 16, 1946, Serial No. 703,628

1 Claim. (Cl. 223—91)

1

My invention relates to garment hangers and has for its principal objects, to generally improve upon and simplify the construction of the existing forms of garment hangers; further, to provide a simple, practical and inexpensive hanger particularly designed for the convenient suspension of garments such as coats, vests, jackets, skirts, trousers and the like, and further, to provide a hanger that includes a spring pressed gripping member shaped so as to be conveniently engaged and lifted from its garment gripping position.

With the foregoing and other objects in view, my invention consists in certain novel features of construction and arrangement of parts which will be hereinafter more fully described and claimed and illustrated in the accompanying drawings, in which:

Fig. 1 is an elevational view of my improved garment hanger with portions of one end in vertical section.

Fig. 2 is an enlarged cross section taken on the line 2—2 of Fig. 1.

Fig. 3 is an enlarged vertical section taken on the line 3—3 of Fig. 1.

Referring by numerals to the accompanying drawings which illustrate a preferred embodiment of my invention, 10 designates the upper member of the hanger body which may be formed of plastics, wood or metal, preferably arch shaped so as to conform to the shape of the shoulders of coats, vests, jackets and like garments, and projecting upwardly from the center of this member 10 is a hook 11, whereby the hanger may be suspended from a rail, hook or other support.

Formed integral with and depending from the end portions of member 10 are short vertically disposed legs 12, which are preferably inset short distances from the ends of said member and formed in these legs are vertically disposed pockets 13 open on the inner sides of said legs.

Connecting the lower ends of legs 12 below the pockets 13 is a straight rail 14. Positioned between member 10 and rail 14 is a slightly arched rail 15 which functions as a handle and seated in the upper central portion of this rail are the lower ends of pins 16 which extend upwardly and are arranged for sliding movement through vertical bores 17 formed in member 10, in the sides of hook 11.

Formed integral with the ends of arched rail 15 are short horizontally disposed rails 18 which normally bear on top of the ends portions of rail 14, and formed through the ends of said rails 18 that are positioned in the pockets 13, are vertically disposed apertures 19.

The ends of pins 20 are seated in the ends of rail 14 and the ends of member 10, which pins extend through the apertures 19 and pockets 13, and mounted on each pin, between the ends of member 10 and the outer ends of rails 18, are expansive coil springs 21.

2

Thus, the springs 21 exert downward pressure on rails 18, so as to grip those portions of garments hanging from rail 14 and underlying said rails 18.

In the use of my improved garment hanger, the shoulder portions of coats, vests, jackets, and the like rest on the upper edge of member 10, while garments such as trousers, slacks and skirts hung over said rail 14 are clamped thereto by the spring pressed rails 18.

To lift the rails 18 from rail 14, it is only necessary to elevate rail 15 by upward pressure thereon, by the fingers or thumb of the hand holding the hanger and during such movement of said rail 15, it is prevented from canting and consequent binding, by the pins 16 which slide freely through bores 17 in member 10, thus providing a positive guide.

Thus it will be seen that I have provided a garment hanger which is simple in structure, inexpensive of manufacture and very effective in performing the functions for which it is intended.

Minor changes in the size, form and construction of the various parts of my improved garment hanger may be made and substituted for those herein shown and described without departing from the spirit of the invention, the scope of which is set forth in the appended claim.

I claim as my invention:

30 In a garment hanger, an arched upper member, short legs depending from the ends of said member, which legs are provided with pockets, a rail integrally connecting the lower ends of said legs, an arched handle disposed between said arched upper member and said rail, short rails carried by the ends of said handle and bearing on top of the end portions of said first mentioned rail, the ends of which short rails extend into the lower portions of said pockets, pins seated in the ends of said upper member and in the lower ends of said legs, which pins extend through said pockets and through the ends of said short rails, expansive springs on said pins within said pockets, and bearing on the ends of said short rails, spaced apertures in the central portion of said arched upper member and vertical guide pins having their lower ends seated in the central portion of said arched handle, with their upper portions slidably arranged in said apertures.

SOLOMON ROSENBERG.
